[57] CLAIM

The ornamental design for a safety propane transporter, as shown and described.

DESCRIPTION

FIG. 1 is a front and left side perspective view of a four sided embodiment of safety propane transporter showing my new design;

FIG. 2 is a front side elevational view thereof, the rear side thereof being identical;

FIG. 3 is a bottom plan view thereof;

FIG. 4 is a top plan view thereof;

FIG. 5 is a left side elevational view thereof, the right side thereof being identical; and,

FIG. 6 is a front and left side perspective view of a three sided embodiment of a safety propane transporter showing my new design; the left side, right side, and rear side of this embodiment being similar to the view of FIG. 2; the front side being visible as shown in this FIG. and FIG. 2 will comprise visible adjacent walls; the bottom of this embodiment being similar to FIG. 3 except that it is three-sided; and the top of this embodiment being similar to FIG. 4 except that it is three-sided.
